United States Patent Office.

CLARENCE DELAFIELD, OF FACTORYVILLE, NEW YORK.

Letters Patent No. 74,204, dated February 11, 1868.

IMPROVEMENT IN WATER-GAUGES.

The Schedule referred to in these Letters Patent and making part of the same.

TO ALL WHOM IT MAY CONCERN:

Be it known that I, CLARENCE DELAFIELD, of Factoryville, county of Richmond, in the State of New York, have invented a certain new and improved Water-Gauge for Steam-Boilers; and I do hereby declare the following to be a full, clear, and exact description of the same, reference being had to the annexed drawing, making part of this specification, in which—

Figure 1 is a vertical longitudinal section, showing the invention as applied to a boiler; and

Figures 2, 3, 4, 5, 6, 7, and 8 are detailed parts of the same, which will be hereinafter referred to as occasion may require.

The following description will enable any one skilled in the arts to which my invention appertains to make and use the same.

In the drawing, *m* represents the boiler-front, in which a tube, *c*, is screwed. The front end of this tube is funnel-shaped or conical in the inside, and in the rear end thereof there is formed a spherical valve-seat, in which the valve *b* is accurately fitted. The stem upon which this valve is made reaches from the valve forward through the tube, and connects to a steam-whistle, *a*, in front of the boiler, and said stem also extends back from said seat, and connects to a float, *R*, which rises and falls with the water in the boiler.

In the rear end of the tube *c* there is a small hole, *V*, made, and in the valve *b* there is also a small hole made, which extends all the way through that part of the valve-stem which reaches forward from the valve and connects to the whistle. Now, this hole *V*, in the tube, and the corresponding hole in the valve-seat, are so made and arranged with reference to each other as to match, that is, come directly opposite each other, when the water sinks so low as to endanger the boiler, whereupon the steam will issue through these holes and blow the whistle *a*; but to show the height of the water in the boiler, at all times, the front end of the valve-stem is connected to a dial-joint, *g*, by means of a small rod, *f*, and a crank, *i*, as shown more fully in fig. 8, this dial-joint swinging on a pivot in the centre of the dial-plate *e e*, which dial-plate is secured by a pair of studs, *X X*, on the front end of the tube *c*, as shown in fig. 3, an oblong hole being made in said plate to allow the end, *k*, of the valve-stem to rise and fall with the float in the boiler.

The front of the dial-plate is shown in fig. 6, which also shows the register-marks, by which the exact height of water in the boiler is indicated.

Having now described the nature and extent of my invention, I claim, and desire to secure by Letters Patent—

1. The use of a funnel-shaped tube, fitted with a valve, and combined with the boiler-skin, substantially as described, by which the escape of the steam around the valve-stem is stopped, and the motion of the float and dial-point provided for.

2. The whistle *a*, in combination with the valve-stem, when said valve-stem is made with a hole through the same, leading from and matching with a hole in the valve-seat, and discharging in the whistle, substantially as described, by which the escape of steam is regulated, and made to sound an alarm at a certain stage of the water.

CLARENCE DELAFIELD.
